Brown Patent Law, P.L.L.C.(57) **CLAIM**

The ornamental design for a coffee dripper for tumbler, as shown and described.

DESCRIPTION

FIG. 1 is a front perspective view of a coffee dripper for tumbler showing my new design.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof in use condition.

The broken lines shown in the drawings represent unclaimed portions of the design and form no part thereof.
